UNITED STATES PATENT OFFICE

2,589,835

SANITARY DISPENSER FOR FOOD BOXES

Joseph H. Malachick, New York, N. Y.

Application June 23, 1947, Serial No. 756,414

1 Claim. (Cl. 222—364)

1. This invention relates to a sanitary food box dispenser.

It is an object of the present invention to provide a removable food box dispenser which will be fitted into a corner of a cardboard box in such a manner that the corner of the box will be rigidly supported and the contents of the box will flow outwardly over a V-shaped space of the dispenser, a cover being provided therein to close the V-shaped opening when the box is upright and out of use, and may be reused by attaching to a new cardboard box.

It is another object of the present invention to provide a food box dispenser adapted to fit the corner of the cardboard box with a measuring means so that measured quantities can be taken from the box, the measuring device being pivoted and able to serve in one position as the cover for the dispenser.

Other objects of the present invention are to provide a food box dispenser which is of simple construction, inexpensive to manufacture and efficient in operation.

According to the invention, the dispenser is formed of inner and outer walls adapted to be extended downwardly over the side walls of the box to retain them therebetween. A top plate extends between the outer walls to which a cover is hinged for closing a V-shaped corner opening over which the box contents are poured.

In another form of the invention, the inner wall is shaped to form a measuring chamber into which a portion of the box contents may be measured. An extension on the cover will be extended into the measuring chamber to prevent the contents of the box, while the measured quantity is being poured, from leaving the box.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of the top portion of a box and of the dispenser embodying the features of the present invention with its cover raised.

Fig. 2 is a perspective view similar to Fig. 1 except that the dispenser has its cover lowered.

Fig. 3 is a cross sectional view taken on line 3—3 of Fig. 2.

Fig. 4 is a collective view of the various parts serving to make up the food dispenser.

2

Fig. 5 is a cross sectional view of a modified form of dispenser in which measuring means are incorporated within the dispenser and with the measuring means dropped to the lowered position so that its cover portion thereof will close the opening at the top of the dispenser.

Fig. 6 is a view similar to Fig. 5 except that the dispenser has been tilted and the cover measuring means has been lowered to permit the outflow of the contents contained within the measuring means.

Fig. 7 is a fragmentary perspective view of a portion of the measuring wall with the stops thereon to limit the outward movement of the cover and measuring device.

Referring now particularly to the first form of the invention shown in Figs. 1 to 4, 10 represents a cardboard box having a top and 11 represents one form of the food box dispenser adapted to be fitted into a top corner of the box. The top corner of the box is pierced with the dispenser 11. The dispenser 11 has an inner wall 12 and an outer wall 13 adapted to be extended downwardly from the corner for some distance. The lower end of the inner wall 12 is bent slightly inwardly, as indicated at 14, whereby to penetrate the corner of the box and permit the easy sliding of the walls 12 and 13 downwardly over the cardboard side walls of the box. The side wall of the box will be rigidly retained between the walls 12 and 13. They extend in two directions from the corner. The inner wall is folded from one piece and downwardly from the top of the outer wall. As viewed in Fig. 4, it will be noted that the top edge of the dispenser has a rounded shape and the inner wall is a continuation of the outer wall except that it is bent down. Inwardly extending portions 15 are bent inwardly at an angle of ninety degrees from the outer wall 13. These projections serve as means to which a top plate 16 can be attached and retained as a support for a hinged cover 17 connected by hinge formations 18 with a hinge formation 19 on the plate 16 and by a hinge pin 21 which is extended through the hinge formations. A spring 23 can be fixed about the hinge pin 21 and extend across the top of the dispenser to retain the cover normally in a closed or lowered position.

When the box 10 is tilted, the cover 17 may be pulled back and the contents of the box will be poured outwardly through the V-shaped space in the corner of the box and formed by the dispenser.

In Figs. 5 and 6, there is shown a measuring device associated with the dispenser. The dis-

penser has an outer wall 25 and an inner wall 26 which extends only part way down the extent of the outer wall 25 and is curved inwardly to provide a chamber 27 into which a portion of the contents can be poured before opening a cover 28. The cover 28 has a portion 29 extending at an angle from the rear of the cover portion and is adapted to pass through the chamber 27 whereby to maintain the chamber closed while the contents therein as indicated in Fig. 6 are dispensed. The portion 29 will come to rest against projections 31 on the inner wall chamber portion 26. As the cover 28 is lowered, the portion 29 will be extended into the box and out of the chamber 27 so as to permit more material to drop into the chamber 27 as the box is tilted.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A sanitary dispenser for a food box, comprising interfitted corner-shaped inner and outer walls for insertion downwardly over the respective inner and outer faces of the corner walls of the box, a narrow top plate extended between the top edges of said walls inward of the apex of said walls leaving a pouring opening between the apex of said walls and the outer edge of said plate, a cover hingedly connected to the outer edge of said top plate and rested on the top edges of said walls to close said pouring opening, said inner wall being rounded inwardly and down-

wardly to provide a measuring chamber within the box, the box having an opening in the top between said corner and said narrow top plate, said opening constituting an entrance to the measuring chamber, said top plate having its outer edge at the inner edge of said box opening, an extension depended from the hinged edge of said cover into said box at a point spaced slightly from the entrance to said chamber to move with said cover, when the cover is pivoted to open said pouring opening, into said chamber to prevent the flow of the contents of the box through the measuring chamber while the contents of the measuring chamber are being emptied, and a projection on the inner wall adjacent the top edge thereof for engagement by the free edge of said extension to limit outward movement of said extension as the measured quantity contents of said chamber are being dispensed.
